UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR OVERSEAMING MACHINES.

Application filed November 11, 1920. Serial No. 423,305.

To all whom it may concern:

Be it known that I, JAMES R. MOFFATT, a citizen of the United States, residing at Chicago, in the county of Cook, State of Illinois, have invented certain new and useful Improvements in Feeding Mechanisms for Overseaming Machines, of which the following is a description, reference being had to the accompanying drawing, and to the figures of reference marked thereon.

The invention relates to new and useful improvements in feeding mechanisms for overseaming machines, and more particularly an overseaming machine of the cup feed type, such as shown, for example, in the Onderdonk Patent 1,137,784, granted May 4, 1915.

An object of the present invention is to provide means for positively driving the outer feed cup or roller by means of a shaft which is so constructed as to permit said outer feed cup or roller to be moved away from the inner feed cup or roller to permit the insertion and removal of the material operated upon.

In the drawings, which show by way of illustration, one embodiment of the invention,

Figure 1 is a view partly in side elevation and partly in vertical section, of a sewing machine embodying my improvements;

Figure 2 is a sectional view on the line 2—2 of Figure 1;

Figure 3 is a view partly in side elevation and partly in vertical section, showing the inner feed cup and the means for operating the same;

Figure 4 is a plan view of the machine with the cover plates for the cross driving shaft removed;

Figure 5 is a sectional view on the line 5—5 of Figure 1;

Figure 6 is a sectional view on the line 6—6 of Figure 1;

Figure 7 is a sectional view on the line 7—7 of Figure 1;

Figure 8 is a detail in side elevation, of a section of the cross shaft, the parts being separated to show the construction;

Figure 9 is a perspective view of the supporting bracket for the outer feed cup;

Figure 10 is a sectional view on the line 10—10 of Figure 4.

The invention above noted is directed to a feeding mechanism for a cup feed type of

sewing machine—that is, a machine wherein two feed cups or rollers rotate about vertical axes and support the material in a vertical plane which is to be stitched. The needle moves in a horizontal path and the looper moves from one side of the material to the other, forming overseaming stitches.

In the present machine, both the inner and the outer feed cups are positively driven. The outer feed cup is mounted so that it may be moved toward and from the inner feed cup to accommodate different thicknesses of material and to permit the insertion and removal of the material to be stitched. The cross driving shaft for positively rotating the outer feed cup is provided with universal joints and a telescoping section, so as to permit this freedom of movement and without disturbing the positive driving connection for the outer feed cup to the train of mechanism operating the same.

Referring more in detail to the drawings, my improvements are shown and applied to a sewing machine consisting of a main casing 1, in which is mounted to reciprocate a needle bar carrying a needle 2. The needle bar, as above noted, reciprocates in a horizontal plane. Co-operating with this needle bar is a looper 3 which moves from one side of the fabric to the other, thus forming an overseaming stitch. This type of machine is common in the art and further description of the stitching mechanism is not thought necessary.

The material is clamped and supported during the stitching operation between an inner feed cup 4 and an outer feed cup 5. The inner feed cup 4 is carried by a shaft 6 mounted in a bracket 7 secured to the casing. At the lower end of the shaft 6 there is an intermittent clutch mechanism 8, which turns the shaft step by step. This clutch mechanism is also very common in the art and a detail description thereof is not thought necessary. The operating arm 9 of the clutch mechanism is connected by means of a link 10 to an arm 11, carried at the lower end of the shaft 12, mounted in suitable bearings on the main casing 1. This shaft 12 carries an arm 13 at its upper end to which an eccentric strap 14 is connected. The eccentric strap co-operates with an eccentric on the main shaft 15. As this main shaft rotates, the shaft 6 will be

given an intermittent or step by step movement in a clockwise direction, as viewed in Figure 2. This turns the inner feed cup step by step and feeds the material a stitch 5 length, the feed cup remaining idle during the time when the needle is in the material.

The outer feed cup 5 is carried by a shaft 16, mounted in a bracket 17. Said shaft is 10 provided with a beveled gear 18 at its upper end which meshes with a beveled gear 19 carried by a cross driving shaft 20. The cross shaft 20 carries a beveled gear 21 meshing with a beveled gear 22, carried by a vertical shaft 23. This vertical shaft 23 is mounted in suitable bearings in the main casing 1. At the lower end of the shaft 23 is a gear 24 which meshes with a gear 25 and the gear 25 in turn meshes with a gear 26 which is fixed to the shaft 6. The shaft 20 20 rotates step by step to feed the material.

Through the gears, the vertical shaft 23 and the cross shaft 20 impart a step by step movement to the shaft 16 carrying the outer feed cup. The outer feed cup is, therefore, 25 positively driven in timing with the inner feed cup and co-operates with the inner feed cup in feeding the material to and from the needle.

30 The bracket 17 is pivoted at 27 to the supporting arm 28, which is shown in detail in Figure 9 of the drawings. Said arm is provided with elongated slots 29—29 through 35 which screws pass into the main casing and thereby the arm is secured to the main casing so that it may be bodily adjusted in a horizontal plane. The pivotal connection is in the form of a short shaft freely journaled in the spaced ears 30—30, carried by the 40 bracket 28. The bracket 17 is clamped to this short shaft by means of a screw 31. Secured to the outer end of the short shaft, forming the pivotal support 27, is an arm 32, which may be connected to a treadle, so 45 that the bracket 17 may be swung on its pivotal support 27. A spring 33 pressing upwardly on the arm 32, normally holds the feed cups in engagement with each other. Said arm 32 is provided with spaced projecting ears 34 and 35, carrying screws 36 50 and 37, respectively. These screws are so disposed as to engage the bracket 28, one above and the other below the same, and serve as limiting means for determining the 55 amount of upward movement given to the outer feed cup when the treadle is depressed and also the inward movement of the outer cup through the action of the spring 33 when the treadle is released.

60 In order that the outer feed cup may be 65 swung toward and from the inner feed cup, the cross shaft 20 is provided with universal joint connections 38 and 39. The shaft between the universal joints 38 and 39 is in the form of two telescoping sections, one

of which is indicated at 40 and the other at 41. The part 40 is in the form of a sleeve and the end of the sleeve is provided with recesses 42, see Figure 8, while the part 41 is in the form of a rod fitting within the 70 sleeve and said rod is provided with projections 43 adapted to engage the recesses 42, respectively.

By this construction of the cross shaft, it will be apparent that the bracket 17 may 75 be swung about the pivotal point 27, the universal joints will swing about each other, to permit this swinging of the bracket, and the shaft carrying the outer feed cup, without disturbing the driving connections with 80 this outer feed cup. The telescoping sections also aid in the swinging of the parts without disturbing the driving connections as will be obvious from the above description. 85

The beveled gears 21 and 22 are housed by a casing 44 which is secured to the bearing 45 for the inner section of the cross shaft 20. The outer gears 18 and 19 are enclosed by a casing 46 which is secured to the bearing 47 for the outer section of the shaft 20, said bearing being mounted on the bracket 17. 90

The bracket supporting the outer feed cup is pivoted above the feed cups and the driving cross shaft for operating the outer feed 95 cup is above the pivotal support for the bracket 17 so that the driving connections for the outer feed cup are entirely out of the way, and at the same time permit free movement of the outer feed cup without in 100 any way disturbing the driving connections. Furthermore, the supporting arm 28 for the bracket 17 may be adjusted upon loosening the screws 29, and the outer feed cup positioned either nearer to or farther from the 105 inner feed cup, as desired.

It is obvious that minor changes in the details of construction and arrangement of parts may be made without departing from the spirit of the invention, as set forth in 110 the appended claims.

Having thus described the invention, what I claim as new and desire to secure by Letters-Patent, is—

1. A sewing machine including inner and outer feed cups, a bracket pivotally supported above said feed cups, and a driving mechanism for said cups including a horizontal shaft disposed above the inner feed cup for driving the outer feed cup, said 115 shaft having flexible parts whereby the bracket may be swung to separate the cups, and beveled gears connecting the respective ends of the horizontal shaft with the feed cups. 120

2. A sewing machine including inner and outer feed cups, a bracket pivotally supported above said feed cups, and driving mechanism for said cups including a horizontal shaft disposed above the inner feed cup for 125 130

driving the outer feed cup, said shaft having spaced universal joints and telescoping sections intermediate the same, said telescoping sections being provided with means whereby one section imparts positive rotation to the other.

3. A sewing machine including inner and outer feed cups, a vertical shaft supporting said inner feed cup, means for intermittently rotating said shaft, a second vertical shaft driven from said shaft supporting the inner feed cup and having a bevel gear at its upper end, a third vertical shaft carrying the outer feed cup and having a beveled gear at its upper end, a pivoted bracket supporting said shaft carrying the outer feed cup, a cross driving shaft having bevel gears meshing with the above mentioned bevel gears, said cross driving shaft having flexible parts whereby the bracket may be swung to separate the cups.

4. A sewing machine including inner and outer feed cups, a vertical shaft supporting said inner feed cup, means for intermittently rotating said shaft, a second vertical shaft driven from said shaft supporting the inner feed cup and having a bevel gear at its upper end, a third vertical shaft carrying the outer feed cup and having a beveled gear at its upper end, a pivoted bracket supporting said shaft carrying the outer feed cup, a cross driving shaft having bevel gears meshing with the above mentioned bevel gears, said cross driving shaft having spaced universal joints and telescoping sections between the same whereby the bracket may be swung to separate the cups, and means whereby one of said telescoping sections imparts positive rotation to the other.

5. A sewing machine including inner and outer feed cups, a vertical shaft supporting said inner feed cup, means for intermittently rotating said shaft, a second vertical shaft driven from said shaft supporting the inner feed cup and having a bevel gear at its upper end, a third vertical shaft carrying the outer feed cup and having a beveled gear at its upper end, a pivoted bracket supporting said shaft carrying the outer feed cup, a cross driving shaft having bevel gears meshing with the above mentioned bevel gears, said cross driving shaft having spaced universal joints and telescoping sections between the same where-

by the bracket may be swung to separate the 55 cups, means whereby one of said telescoping sections imparts positive rotation to the other, and spaced independent casings for housing the bevel gears at the ends of the cross shaft.

6. A sewing machine including inner and outer feed cups, a vertical shaft supporting said inner feed cup, means for intermittently rotating said shaft, a second vertical shaft driven from said shaft supporting the 65 inner feed cup and having a bevel gear at its upper end, a third vertical shaft carrying the outer feed cup and having a beveled gear at its upper end, a pivoted bracket supporting said shaft carrying the outer feed 70 cup, a cross driving shaft having bevel gears meshing with the above mentioned bevel gears, a bearing on said pivotal bracket for supporting the outer end of said cross driving shaft, a bearing for supporting 75 the inner end of said cross driving shaft, said cross driving shaft having flexible parts between the bearings whereby the pivoted bracket may be swung to separate the feed cups.

7. A sewing machine including inner and outer feed cups, a vertical shaft supporting said inner feed cup, means for intermittently rotating said shaft, a second vertical shaft driven from said shaft supporting the 85 inner feed cup and having a bevel gear at its upper end, a third vertical shaft carrying the outer feed cup and having a beveled gear at its upper end, a pivoted bracket supporting said shaft carrying the outer feed cup, 90 a cross driving shaft having bevel gears meshing with the above mentioned bevel gears, a bearing on said pivoted bracket for supporting the outer end of said cross driving shaft, a bearing for supporting the inner 95 end of said cross driving shaft, said cross driving shaft having flexible parts between the bearings whereby the pivoted bracket may be swung to separate the feed cups, a casing secured to the bearing for the outer 100 end of the cross shaft and housing the bevel gears adjacent said outer end, and a separate spaced casing secured to the bearing for the inner end of the cross shaft and housing the bevel gears adjacent the same.

In testimony whereof, I affix my signature.

JAMES R. MOFFATT.
